UNITED STATES PATENT OFFICE.

JAMES D. HULL, OF BUFFALO, NEW YORK, ASSIGNOR OF ONE-FOURTH OF
HIS RIGHT TO PRATT & LETCHWORTH, OF SAME PLACE.

DESIGN FOR A COCKEYE-CLIP.

SPECIFICATION forming part of Design No. 11,827, dated June 22, 1880.

Application filed May 5, 1880. Term of patent 14 years.

To all whom it may concern:

Be it known that I, JAMES D. HULL, a citizen of the United States, residing at Buffalo, in the county of Erie and State of New York, have invented and produced a new and original Design for Cockeye-Clips, of which the following is a specification, reference being had to the accompanying drawing, forming part thereof.

10 This design relates to the configuration of the clip or metallic strap which passes around the cross-bar of the cockeye and embraces the end of the trace to which the clip is riveted for securing the cockeye to the trace.

15 The accompanying drawing represents a side elevation of the clip applied to a cockeye.

A represents a cockeye, and B the clip or bent metallic strap which is applied thereto, and consists of two parallel legs, D E, connected by a bent neck, F, which embraces the cross-bar c of the cockeye. The front leg, E, of the clip is contracted forwardly from the

point where it leaves the jaws g of the cockeye to the points h. It then expands, forming two projecting points or salient angles, i, opposite the first rivet-hole f. It is then again contracted, as shown at l, and terminates in an oval leaf, k, which contains the second rivet-hole f.

The edges of the leg E may be beveled, as indicated in the drawing.

The rear leg, D, of the clip, which is not ordinarily visible when applied to the trace, may be made straight, as shown.

I claim—

35 The design for a cockeye-clip, consisting of the configuration of the front leg, E, having contracted portions h l, projecting angles i, and oval terminal leaf k, as herein shown and described.

JAS. D. HULL.
